United States Patent Office

Des. 208,452
Patented Sept. 5, 1967

208,452

NECKTIE TAG, OR SIMILAR ARTICLE

Richard M. Aron, Stamford, Conn., assignor to M. Aron Corporation, New York, N.Y., a corporation of New York

Filed Dec. 9, 1966, Ser. No. 4,977

Term of patent 14 years

(Cl. D1—8)

I claim:

The ornamental design for a necktie tag or similar article, as shown.
